Patented June 1, 1880.

UNITED STATES PATENT OFFICE.

THOMAS J. STEARNS, OF BOSTON, MASSACHUSETTS, ASSIGNOR TO ROXBURY CARPET COMPANY, OF SAME PLACE.

DESIGN FOR A CARPET.

SPECIFICATION forming part of Design No. 11,801, dated June 1, 1880.

Application filed April 7, 1880. Term of patent 3½ years.

To all whom it may concern:

Be it known that I, THOMAS J. STEARNS, of Boston, in the county of Suffolk and State of Massachusetts, have invented a new and original Design for Carpets, of which the following is a specification.

My present design is illustrated in the accompanying photograph, forming part of this specification, and to which reference is made in the following description.

The design consists of small blocks forming mosaic work, arranged in irregular geometric figures upon a plain ground, as shown.

I claim—

The design for a carpet herein shown and described, consisting of the mosaic work arranged in irregular geometric forms upon a plain ground, as set forth.

In testimony whereof I have signed my name to this specification, in the presence of two subscribing witnesses, this 1st day of April, A. D. 1880.

THOMAS J. STEARNS.
